(57) **CLAIM**

The ornamental design for a key body, as shown and described.

DESCRIPTION

FIG. 1 is a front and side perspective view of a key body showing my new design;

FIG. 2 is a front elevation view thereof, the rear elevation view being a mirror image thereof;

FIG. 3 is a right side elevation thereof, the left side elevation view being a mirror image thereof;

FIG. 4 is a top plan view thereof;

FIG. 5 is a bottom plan view thereof;

FIG. 6 is a front and side perspective view of a key body;

FIG. 7 is a front elevation of FIG. 6;

FIG. 8 is a right side elevation of FIG. 6, the left side elevation view being a mirror image thereof;

FIG. 9 is a rear elevation view of FIG. 6;

FIG. 10 is a bottom plan view of FIG. 6;

FIG. 11 is a front and side perspective view of a key body;

FIG. 12 is a front elevation of FIG. 11, the rear elevation view being a mirror image thereof;

FIG. 13 is a right side elevation of FIG. 11, the left side elevation view being a mirror image thereof; and,

FIG. 14 is a bottom plan view of FIG. 11.

The top plan view of embodiment 2 and 3 is identical to FIG. 4 of the first embodiment. The broken lines illustrating environment are for illustrative purpose only and form no part of the claimed design.
